ATTORNEY

UNITED STATES PATENT OFFICE.

HARRY ALLEN HERRON, OF HARDIN, ILLINOIS.

1,280,465.

Specification of Letters Patent.

Patented Oct. 1, 1918.

Application filed March 15, 1918. Serial No. 222,631.

To all whom it may concern:

Be it known that I, HARRY A. HERRON, a citizen of the United States, residing at Hardin, in the county of Calhoun and State 5 of Illinois, have invented new and useful Improvements in Mattocks, of which the following is a specification.

This invention relates to a new and improved mattock and it consists in the novel 10 features hereinafter described and claimed.

An object of the invention is to provide a mattock having a head provided with an ax blade and a grubbing blade the said 15 blades being located at the opposite sides of the head. The ax blade is provided with a rear edge which lies in the same plane as that in which the end of the eye of the head lies and the grubbing blade is provided with a rear side which lies in a plane at an acute 20 angle with relation to the plane in which the rear edge of the ax blade lies whereby the rear edge of the ax blade may be used as a fulcrum during the grubbing operation to assist in forcing the grubbing blade 25 through the soil and in lifting the same.

In the accompanying drawing:—

Figure 1 is a perspective view of the mattock head.

Fig. 2 is a side elevation of the same. 30 The other figures are detailed views of the features of the invention.

The mattock head includes an eye 1 having an ax blade 2 and a grubbing blade 3 integrally joined therewith and at the opposite sides thereof. The eye is provided with the usual tapered opening 4 through which a handle or staff may be inserted. The ax blade 2 is provided with a rear flat edge 5 which lies in the same plane as that 35 in which one of the ends of the eye 1 lies. The said blade 2 is provided at its inner portion with a longitudinally disposed straight cutting edge 6 passed under its end with a transversely disposed cutting edge 7.

40 The grubbing blade 3 is provided at its rear side with a plane surface 8 which lies at an acute angle to the plane in which the edge 5 of the blade 2 lies. The rear portion of the blade 3 is slightly chamfered as 45 at 9 at its outer end. And the blade 3 is

provided at its outer end with a transversely disposed cutting edge 10. The transverse thickness of the blade 3 gradually increases from the cutting edge 10 to the side of the eye 1 and the inner portion of 55 the blade 3 in the vicinity of the longitudinal edges thereof is cut away as at 11 thereby providing a spine or ridge 12 which extends approximately from the eye 1 to the cutting edge 10 of the blade 3. Hence it 60 will be seen that the median longitudinal dimension of the blade 3 is disposed at an acute angle to the corresponding dimension of the blade 2 and the blade 3 is thickened centrally from the eye 1 toward its cutting 65 edge 10.

In operation as a grubbing implement the blade 3 is used and when the same is inserted in the soil the handle or staff which is attached to the head may be swung whereby the straight edge 5 of the blade 2 may be used as a fulcrum against the hard soil for moving the blade 3 through the soil loosening and lifting the same. 70

By reason of the fact that the surface 75 5 of the blade 3 is plane the said blade 3 may be readily forced into the soil and in view of the fact that the blade 3 is provided with the thickened portion or ridge 12 the blade 3 is strengthened and is not liable to 80 be broken off when it is forced through the soil or when it is lifting the same. When the implement is used for cutting roots or the like the blade 2 is used and the edge 7 may be forced against the roots or the 85 edge 6 of the blade 2 may be forced under or beyond the roots and then the head may be swung whereby the edge 2 may be caused to sever the roots as the head swings or turns. 90

In this event the blade 3 may serve as a fulcrum for the blade 2 to assist the cutting operation.

Having described the invention what is claimed is:—

95 A mattock head comprising an intermediate portion provided with an eye, an ax blade joined with the eye portion and having a rear edge lying in the same plane as that in which the end of the eye lies, the ax 100

blade being provided at its inner portion with a longitudinally disposed cutting edge, and a grubbing blade attached to the eye portion and having at its outer side a plane 5 surface disposed at an acute angle to the plane in which the rear edge of the ax blade lies, the said cutting blade being provided

with a longitudinally disposed strengthening rib located at its inner side, the cutting edge of the ax blade lying in the same 10 plane as that in which the median longitudinal dimension of the rib lies.

In testimony whereof I affix my signature.
HARRY ALLEN HERRON.
